UNITED STATES PATENT OFFICE.

CHARLES STEIN, OF FALL CREEK, WISCONSIN.

IRONING-BOARD.

1,110,971.

Specification of Letters Patent. Patented Sept. 15, 1914.

Application filed February 24, 1914. Serial No. 820,635.

To all whom it may concern:

Be it known that I, CHARLES STEIN, a citizen of the United States, residing at Fall Creek, in the county of Eau Claire and State 5 of Wisconsin, have invented certain new and useful Improvements in Ironing-Boards, of which the following is a specification, reference being had to the accompanying drawings.

10 This invention relates to certain improvements in ironing boards and has relation more particularly to a device of this general character of a convertible type whereby the same may be employed with equal facility 15 as a step-ladder; and the object of the invention is to provide a device of this type having novel and improved means whereby the device may be adjusted, as desired, with convenience and facility and which may be 20 compacted within a minimum of space when the same is not in use for either of its purposes.

The invention consists in the details of construction and in the combination and arrangement of the several parts of my improved ironing board whereby certain important advantages are attained and the device is rendered simpler, less expensive and otherwise more convenient and advantageous 30 for use, all as will be hereinafter more fully set forth.

The novel features of the invention will be carefully defined in the appended claims.

In order that my invention may be the 35 better understood, I will now proceed to describe the same with reference to the accompanying drawings, wherein—

Figure 1 is a view in side elevation of an ironing board constructed in accordance with 40 my invention; Fig. 2 is a view in perspective of my device adjusted in position to be employed as a step-ladder; and Fig. 3 is a view in side elevation illustrating the device in folded position.

45 As disclosed in the accompanying drawings, 1 denotes the ironing board which may be of any desired configuration and dimensions, the head end of such board 1 being provided with a depending flange 2 also 50 adapted to serve as a top rest when the device is in use as a step-ladder. Suitably connected to the under surface of the board 1 and the adjacent face of the flange 2 are the predetermined spaced blocks 4 with 55 which are pivotally engaged the side members 5 of the step-ladder 6, such step-

ladder 6 being substantially the same length as the ironing board 1 and being adapted to fold thereagainst when not in use. In close proximity to the opposite end or foot of the 60 ironing board 1 are the blocks 7 with which are pivotally engaged an extremity of the elongated members 8, such elongated members being of a predetermined length and adapted to serve as a supporting or bracing 65 member for the device as herein disclosed. Intermediate their lengths, each of the side members 5 of the step-ladder 6 is provided with an opening 9 adapted to register with an opening 10 produced in each of the elongated members 8 and through which is adapted to be projected a headed rod 11, the free extremity of which being threaded and adapted to be engaged by a clamping member 12, herein shown as a winged nut, whereby it will be readily perceived that such 70 rod 11 serves as an assembling means for the device and maintains the same in such relative adjustment as to permit the device to be employed with convenience and facility as an ironing board as particularly illustrated in Fig. 1 of the drawings. The free extremities of the side members of the step-ladder 6 are also provided with additional alining openings 14 with which are adapted 75 to register the openings 15 produced in the adjacent extremities of the elongated members 8, and through such registering openings is adapted to be directed the headed rod 11 whereby the device is maintained in such 80 assembled position, as is clearly shown in Fig. 2, to permit the same to be employed as a step-ladder.

In Fig. 3 the device is shown in folded or compacted position whereby it will be readily perceived that the same will occupy a minimum of space when not in use and when in such adjustment it will be observed that the retaining rod 11 is directed through the alining openings 14 whereby the same is 85 held against displacement or loss and it will also be readily observed in Fig. 3 that the relative positions of the blocks 4 and the blocks 7 are such as to cause the side members 5 and the elongated members 8 to be 90 positioned in parallel relation when in inoperative position.

From the foregoing description, it is thought to be obvious that an ironing board constructed in accordance with my invention 110 is of an extremely simple and comparatively inexpensive nature and is particularly well

adapted for use by reason of the convenience and facility with which it may be assembled and adjusted to either of the usages for which it is intended and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A device of the character described comprising a board, a step-ladder having corresponding extremities of its side members pivotally engaged therewith adjacent an end thereof, such side members intermediate their length and in close proximity to their free extremities being provided with alining openings, elongated members pivotally connected with the board adjacent the opposite end thereof and being provided with alining openings intermediate their length and in close proximity to the free extremities thereof, the openings of the elongated members being adapted to register with the openings in the side members of the ladder, and a retaining means adapted to be directed through the alined openings of the elongated members and the side members of the step-ladder whereby the same are maintained in requisite assemblage, such retaining member being common to each of the side members of the step-ladder and its coacting elongated member.

ladder whereby the same are maintained in requisite assemblage.

2. A device of the character described comprising a board, a step-ladder having corresponding extremities of its side members pivotally engaged therewith adjacent an end thereof, such side members intermediate their length and in close proximity to their free extremities being provided with alining openings, elongated members pivotally connected with the board adjacent the opposite end thereof and being provided with alining openings intermediate their length and in close proximity to the free extremities thereof, the openings of the elongated members being adapted to register with the openings in the side members of the ladder, and a retaining means adapted to be directed through the alined openings of the elongated members and the side members of the step-ladder whereby the same are maintained in requisite assemblage, such retaining member being common to each of the side members of the step-ladder and its coacting elongated member.

In testimony whereof I hereunto affix my signature in the presence of two witnesses.

CHARLES STEIN.
